UNITED STATES PATENT OFFICE.

WILLIAM RIPPEY, OF ALLEGHENY CITY, PENNSYLVANIA.

FURNACE FOR THE COMBUSTION OF NATURAL GAS.

SPECIFICATION forming part of Letters Patent No. 337,868, dated March 16, 1886.

Application filed June 12, 1885. Serial No. 168,445. (No model.)

To all whom it may concern:

Be it known that I, WILLIAM RIPPEY, of Allegheny City, in the county of Allegheny and State of Pennsylvania, have invented a new and useful Improvement in Furnaces for the Combustion of Natural Gas; and I do hereby declare the following to be a full, clear, and exact description thereof, reference being had to the accompanying drawings, forming a part 10 of this specification, in which—

Figure 1 is a vertical longitudinal section of my improved furnace on the line $x x$ of Fig. 2, which is a front view of the same.

Like letters of reference indicate like parts.

15 The purpose of my invention is to improve the construction of puddling and heating furnaces and to increase their efficiency of operation.

My invention consists in the combination 20 and arrangement of a gas and air mixing chamber and a combustion-chamber, as is hereinafter described.

The fuel used in the furnace is gas—preferably natural gas—which is introduced into the 25 combustion-chamber a through a pipe, b , which traverses the wall of the chamber, and at its end is provided with the ordinary perforated T-burner. The lower part of the combustion-chamber is made of contracted diam- 30 eter, but little wider than sufficient to accommodate the burner, and the latter is situate a little above the bottom of the chamber. The air-flue has its adit into the contracted part of the combustion-chamber at a point, c , below 35 the level of the gas-burner. Except for this flue, the combustion-chamber is preferably closed from communication with the surrounding air.

Somewhat above the level of the gas-burner 40 the contracted combustion-chamber begins to widen by a gradual flaring of its walls toward the fire-bridge in one direction, and toward the front wall of the furnace in the opposite direction. Considering the limits of the combustion-chamber to lie between the ground-level underneath the pipe b and the level of the bridge-wall, it consists of two parts—the contracted portion a , into which the air-flue c and burner b enter, and which I will call the 45 50 “neck” or “mixing-chamber,” and the upper expanded part, a' , which is the “throat” or “combustion-chamber” proper.

The operation of the furnace, when thus built, is as follows: The air entering the flue c beneath the gas-burner is, by reason of the contracted throat of the combustion-chamber, guided directly upon the gas in a vigorous draft, which causes the air and gas to come into intimate contact, and to be thoroughly mixed at the time when they reach the base 60 of the throat a' . At this point the mingled gases suddenly begin to expand and fill the entire throat with somewhat rarefied burning fuel. This expansion and rarefaction mix the gases even more thoroughly than before, and 65 retard their passage sufficiently to cause complete combustion in the throat of the chamber and in the furnace-hearth before they reach the stack. This quality is materially aided by the fact that the throat flares by a straight and 70 gradual taper, as distinguished from an expansion made by the addition of a rectangular chamber of greater width than the mixing-chamber, because there are no spaces unex- 75 posed to draft in which eddies of air and gas might form to hinder the draft and prevent thorough mixture.

The distinctive advantages of the foregoing elements of my invention consist in the perfect combustion of the gas. 80

The principal objection to the use of natural gas in puddling and heating furnaces is, that its high pressure and other causes prevent the consumption of the whole amount of the fuel in the body of the furnace. A great quantity of it reaches the stack unconsumed, and burns there, to the injury of the masonry and without any good effect on the metallurgical operations of the furnace. So imperfect is the combustion in the ordinary furnace that the 85 heat of the puddling-chamber decomposes the elements of the natural gas, and a deposit of incombustible graphite of considerable density and hardness is formed on the bridge-wall. Besides the loss of fuel which this entails, there 90 must be some heat lost in the formation of this deposit, both of which operate to the hurt of the furnace. I have found that all these objections are obviated by use of my improvement. It will be noticed that the combustion-chamber extends considerably farther below the level of the working-chamber than usual 95 in prior furnaces, by which construction more space is given for admixture of the gases. 100

As incidents to the furnace hereinbefore described, my invention further consists in a novel arrangement of the air-flue, whereby the air is somewhat heated before it reaches the neck of the combustion-chamber, and in an arrangement of the inner wall of the furnace for economizing heat and making its supply more regular.

A part of the front wall of the furnace is made double, with a vertical space, *c'*, between the inner wall, *d*, and the outer wall, *e*, thus formed. This space is coextensive with the mixing-chamber *a*, and preferably reaches a little above it, being separated therefrom only by the thin inner wall, *d*. The outer wall is perforated by a flue or port, *f*, which enters the flue *c'* at a point near its top, and the air-port *c*, which enters the combustion-chamber, traverses only the inner wall, *d*, at or near the bottom of the vertical flue-space. The air of the combustion-chamber is by these means obliged to enter the flue *f*, and in traversing the flue *c'* and the port *c* becomes considerably heated by contact with the chamber-wall *d* and has its burning qualities considerably bettered.

The fire-wall *h* of the furnace has its outer face made perpendicular, and the inner face angular, to conform to the shape of the combustion-chambers. The consequence is, that the wall is very thick, and when it becomes heated acts as a reservoir to distribute the heat evenly in case of any irregularity in the flow of the gas.

I do not desire to claim, broadly, a contracted mixing-chamber leading into a larger combustion-chamber; but

What I claim as my invention, and desire to secure by Letters Patent, is—

1. In a furnace for combustion of gas, the combination of a combustion-chamber consisting of a contracted mixing-chamber or neck and an expanded throat tapering in straight lines both from the bridge-wall and from the front wall of the furnace directly above the mixing-chamber or neck and communicating therewith, a gas pipe or flue entering the contracted mixing-chamber or neck below the expanded throat, and an air-port entering the mixing-chamber below the gas pipe or flue, substantially as and for the purposes specified. 40 45

2. In a furnace for combustion of gas, the combination of a combustion-chamber consisting of a contracted mixing-chamber or neck and an expanded throat above the mixing-chamber or neck and communicating therewith, a gas pipe or flue entering the contracted mixing-chamber or neck below the expanded throat, an air-port entering the mixing-chamber below the gas pipe or flue, and a vertical air-flue made in the front wall 55 60 of the furnace adjacent to the combustion-chamber and discharging thereinto through the said air-port, substantially as and for the purposes described.

In testimony whereof I have hereunto set my hand this 11th day of June, A. D. 1885. 65

WILLIAM RIPPEY.
